CLAIM

I claim, the ornamental design for a chair, as shown and described.

DESCRIPTION

FIG. 1, is a top right perspective view of the chair, showing my new design;

FIG. 2, is a front elevation view thereof;

FIG. 3, is a rear elevation view thereof;

FIG. 4, is a right side elevation view thereof;

FIG. 5, is a left side elevation view thereof;

FIG. 6, is a top plan view thereof; and,

FIG. 7, is a bottom plan view thereof.

The dashed lines shown in FIGS. 1-5, and 7, for example the cross support bars of the chair in FIG. 7, indicate environmental structures and as such, do not form a part of the claimed design.
